MELTING AND DRYING MACHINE

John B. Sweeney, McKeesport, Pa.

Application July 11, 1940, Serial No. 344,994

9 Claims. (Cl. 37—12)

This invention relates to a melting and drying machine and more particularly to a machine especially designed and adapted for use for clearing roadways and the like of snow and ice.

It is the particular aim of the invention to provide a device having means for melting snow and ice, means including suction conveying means for removing the water from the melted snow and ice and means for brushing and wiping the surface to thereby remove the snow and to dry the surface over which the machine is passing.

Still a further aim of the invention is to provide a device capable of use for removing water from roadways or from airport runways and especially adaptable for draining puddles and for drying the surface after the water has been removed.

Still a further object of the invention is to provide a machine adapted for use in the cleaning of muddy roadways including means for draining water therefrom and for drying the roadway surface by the application of heat.

Other objects and advantages of the invention will hereinafter become more fully apparent from the following description of the drawings, which illustrate a preferred embodiment of the invention, and wherein:

Figure 1 is a top plan view showing the apparatus mounted on a motor vehicle,

Figure 2 is a side elevational view of the same, Figure 3 is an enlarged longitudinal vertical sectional view taken substantially along the plane of the line 3—3 of Figure 1,

Figure 4 is an enlarged transverse vertical sectional view taken substantially along the plane of the line 4—4 of Figure 1, and

Figure 5 is a cross sectional view of the brush and wiper blade.

Referring more particularly to the drawings, wherein like reference characters designate like or corresponding parts throughout the different views, 10 designates generally a portion of a conventional motor vehicle on which the apparatus, designated generally 11, and comprising the invention is mounted.

Apparatus 11 includes a heating device, designated generally 12, which includes a container 13 having an open bottom 14. The rear end of the container 13 is provided with a rearwardly extending arm or arms 15 pivotally connected to an arm or arms 16, secured to and extending forwardly from the forward end of the truck 10. The rear end of the container 13 is supported

relatively to a surface indicated by the line 17 over which the apparatus 11 is adapted to be moved by means of wheels or casters 18.

5 A supporting frame 19 is mounted on the forward end of the vehicle 10. An arm 20 is pivotally connected at one end to the upper end of the frame 19 and is provided at its opposite end with a depending hanger 21 which is pivotally connected, intermediate of its ends, thereto. The 10 ends of the hanger 21 are pivotally connected by means of the eye fastenings 22 to a forward end of the top of the container 13 for supporting the forward end of the heating device 12.

As best seen in Figures 3 and 4, the top wall, 15 side walls, and rear wall of the container 13 are provided with space wall portions forming air chambers 23 for insulating said walls. The container 13 is provided with a front wall 24 which terminates above the open bottom 14. A door or closure 25 is hingedly connected at 26 to the lower end of the wall 24 and depends therefrom to the open bottom 14. Door 25 extends from side to side of the container 13 and is held by gravity in a depending, closed position, as seen in full lines in Figure 3. The hinge means 26 is slidably connected to the wall 24 for vertical movement relatively thereto and the door 25 is adapted to be raised and lowered relatively to the open portion of the forward end of the container 13 by means of a pulley 27 journaled in the upper ends of a pair of standards 28 which are secured to and rise from the forward end of the heating device 12. A cable 29 is wound on the pulley or reel 27 and is connected at its free end by means of an eye screw 30 to the door 25. A hand crank 31 is attached to the shaft of the reel 27 for winding and unwinding the cable 29 for raising and lowering, respectively, door 25.

40 A burner plate 32 is supported in a horizontal position in the container 13, intermediate of its top and bottom by means of brackets 33 which are secured to the inner surfaces of the side walls thereof and also by means of bolts 34 which extend upwardly from the plate 32 through the top wall of the container 13. The upper, threaded ends of the bolts 34 are provided with adjusting nuts 35 by means of which plate 32 may be adjusted vertically relatively to the container 13.

45 A burner 36 is supported behind the container 13 by means of a plurality of eye screws 37 having the eyelets thereof engaging end portions of a manifold pipe of the burner 36. The upper, threaded ends of the eye screws 37 engage threaded openings in arms 38 which are secured to and project from the rear end of the con-

tainer 13. Burner 36 is provided with a plurality of jets 39 which extend through the rear wall of the container 13 beneath the burner plate 32.

A blade or shovel 40 is pivotally mounted behind and adjacent heating device 12 by means of brackets 41 which are secured to the forward end of the vehicle 10. The lower edge of the blade 40 may be adjustably positioned relatively to the surface 17 by means of a lever 42 equipped with latch means 43 or may be held yieldably in engagement with the surface 17 by spring means 44.

Blade 40 is disposed transversely of the direction of movement of the vehicle 10 as is also a box or sump 45 which is disposed therebehind. Box 45 is supported beneath the vehicle 10 by arms 46 which are preferably sufficiently resilient to permit the box 45 to yield to pass over uneven portions or humps on the surface 17. Box 45 is provided with an open rearwardly and downwardly inclined portion 47 in the lower part of its front wall, which extends from end to end thereof and which is provided with a mesh wire fabric cover 48. The box 45 is provided with a recess 49 in its rear wall for receiving a pipe 50 which opens at 51 into the box 45. Recess 49 and pipe 50 extend substantially from end to end of the box 45.

A brush or broom 52 is mounted beneath the vehicle 10, intermediate of its ends, and extends substantially from side to side thereof and is disposed at an oblique angle to the direction of movement of the vehicle. Brush 52 is supported by the nut and bolt fastenings 53 which are hung from the chassis of the vehicle 10 and which are provided with expansion coil springs 54 for yieldably holding the bristle portion 55 of brush 52 engagement with surface 17. A rubber wiper blade 56 is disposed behind and substantially contiguous with the brush 52 and supported by brackets 57 secured to the head of the brush and extending rearwardly therefrom.

A fuel tank 58 is mounted on vehicle 10 and is provided with a tube or hose 59 extending to the burner 36. An internal combustion engine 60 is disposed between the fuel tank 58 and the cab 61 of vehicle 10. A suction pump 62 is mounted on one side of the motor 60 and a rotary blower 63 is mounted on the opposite side thereof. Pump 62 and blower 63 are connected to and driven by the driven shaft 64 of the motor 60. Blower 63 is connected with the fuel line 59 for supplying a charge of air thereto for atomizing the fuel discharged under pressure from the jets 39. A hose or pipe 65 leads from the pipe 50 through the suction pump 62 and is supported at its opposite end by a frame 66 for discharging laterally of the vehicle 10.

An hydraulic pump 67 provided with a plurality of control valves, not shown, is mounted in the cab 61. A hose 68 leads from the pump 67 to an hydraulic ram 69, connected at one end to the frame 19 and at its opposite end to the arm 20, intermediate of the ends thereof, for raising and lowering the forward end of the heating device 12. A hose or pipe 70 extends from the hydraulic pump 67 to an hydraulic ram 71 which is connected at one end to vehicle 10 and at its opposite end to the broom 52 raising and lowering said broom and the wiper blade 56.

From the foregoing it will be apparent that the burner 36 will heat the bottom portion of container 13 for melting snow and ice which is moving through and beneath said heating device 12. The burner plate 32 functions to control the

volume of the heat and is adjustable for the purpose of varying the size of the portion of the container, beneath the plate 32, which is heated by burner 36, to thereby regulate the volume of the heat. Door 25 is adapted to be opened inwardly by the pressure of the snow and ice caused by the forward movement of the vehicle 10 to admit the snow and ice to the bottom half of container 13. Where the accumulation of snow and ice is insufficient to open the door 25 said door may be raised to an opened position by means of the reel 27, as heretofore explained. Where the snow and ice is too deep to pass under the burner plate 32, when in its lowered position, the heating device 12 may be raised to an upwardly inclined position by the ram 69, as illustrated in dotted lines in Figure 2. The water resulting from the snow and ice is removed, after having been melted by heating device 12, by being drawn by suction into the sump 45 through opening 47, and conveyed therefrom by the suction created by the pump 62 through pipe 65 and discharged from the free end of said pipe laterally of the vehicle 10. Any unmelted snow or ice left on the surface 11 after the heating device 12 has passed thereover will be removed by the blade 40 and prevented thereby from reaching sump 45. The path thus cleaned by the heating device 12 and the suction means, as described, is engaged thereafter by the broom 52 for brushing any excess water to one side thereof after which the blade 56 wipes the path so that the amount of moisture remaining thereon will be insufficient to freeze and cause a film of ice on the cleared path.

Various modifications and changes are contemplated and may obviously be resorted to as only a preferred embodiment of the invention has been disclosed, and the right is therefore reserved to make such variations and changes in the construction and arrangement of the parts forming the invention as do not depart from the spirit and scope of the invention as hereinafter defined by the appended claims.

45 I claim as my invention:

1. A device of the class described comprising a heating device mounted in front of and supported by a motor vehicle for receiving and melting snow on a surface over which the heating device is being moved, an elongated box disposed behind and transversely of the heating device, said box having an open front, a conduit leading from said box and having a discharge end projecting laterally from the vehicle, and a suction pump mounted on the vehicle for pumping water from the box through said conduit.

2. A device as in claim 1, comprising a fuel tank mounted on the vehicle, a burner associated with said heating device, and a blower connected to the burner for atomizing the fuel.

3. A device as in claim 1, comprising a broom disposed behind the box and at an oblique angle thereto, yieldable means for urging the broom downwardly and into engagement with said surface, and a rubber wiping blade disposed behind the broom for wiping the surface.

4. A device as in claim 1, said heating device comprising a container having an open bottom adapted to be disposed above and adjacent said surface, said container having a front door adapted to be opened inwardly by the pressure of the snow, and heating means disposed in the container and including a horizontally disposed burner plate.

5. A device as in claim 1, comprising a shovel connected to the vehicle and disposed between the heating device and box for scraping the surface to remove unmelted snow and ice.

6. A device as in claim 1, said heating device being pivotally connected to the forward end of the vehicle, and hydraulic means for supporting and for raising and lowering the forward end of the heating device.

7. A device of the character described comprising in combination with a motor vehicle, a sump suspended from the vehicle and disposed adjacent a surface over which the vehicle is moving, suction conveyor means connected to said sump for pumping water from the surface, means for heating the surface, and means for yieldably engaging the surface for brushing and wiping the excess moisture therefrom.

8. A device as in claim 7, said heating means including a box having a heated bottom portion, a hinged door for closing the forward end of the

bottom portion of the box, said door being adapted to be opened by the pressure of the snow when the device is moving in a forward direction, and means for raising the door relatively to the box.

9. Mechanism for removing snow and ice from a highway or other surface, comprising a carrier structure adapted to move over the surface, means connected with the carrier structure for heating the surface to melt snow and ice therefrom, mechanism supported by the carrier behind said means for scooping up water and slush from the surface, means for conveying the scooped-up water and slush away from said mechanism, and a surface wiping unit supported by the carrier rearwardly of said mechanism and including an elongated wiper element adapted to be arranged transversely of the carrier and obliquely to the path of travel thereof to wipe off from the surface moisture not removed by said mechanism.

JOHN B. SWEENEY.
